UNITED STATES PATENT OFFICE.

THOMAS CLARKSON, OF CHELMSFORD, ENGLAND.

FEED-WATER-SUPPLY APPARATUS FOR STEAM-GENERATORS.

1,350,988.

Specification of Letters Patent. Patented Aug. 24, 1920.

Application filed September 4, 1918. Serial No. 252,620.

To all whom it may concern:

Be it known that I, THOMAS CLARKSON, subject of the King of England, residing at Chelmsford, Essex, in England, have invented certain new and useful Improvements in Feed-Water-Supply Apparatus for Steam-Generators, of which the following is a specification.

This invention relates to feed water supply apparatus for steam generators more particularly the mechanism by means of which the movements of a float regulator can be utilized to control the water delivered by the feed pump.

According to this invention the suction valve of the pump is adapted to be lifted and held off its seat, so as to prevent delivery of the water drawn into the pump, by a lever mounted on a shaft which is rocked by the movements of a float which result from variations in the level of the water in the generator, while the rockshaft has imparted to it a constant reciprocating movement in the direction of its axis whereby the shaft is kept free so that the application of only a small force is necessary to rock it. One end of the rockshaft is carried by a stuffing box through which it passes into a chamber whence the water is drawn past the suction valve and the reciprocating motion of the rockshaft obviates any tendency for this stuffing box to offer such resistance to the rotation of the shaft as will prevent the float movements being imparted through the shaft to the suction valve of the pump. On the end of the rockshaft within the pump chamber is a lever which can so act on the suction valve as to lift and support this valve off its seat and retain it so until the water level in the generator has fallen sufficiently to cause the float to move and permit the suction valve again to seat itself. While this valve is lifted the water drawn in by the pump is merely forced back again to the tank and is not delivered to the generator. The necessary reciprocating movements may be imparted to the rockshaft in various ways but conveniently by a lever which bears against the end of the rockshaft, hardened bearing surfaces between these parts being provided.

This lever is moved by means of suitable mechanism from some convenient source of power so that the shaft is constantly pushed by the lever in one direction. The return movement is brought about preferably by the action of a spring. Various lever and

link connections may be employed between the rockshaft and the float spindle.

The accompanying drawings illustrate by way of example one method of putting the invention into practice. In these drawings.

Figure 1 is a vertical sectional elevation of the pump and shaft by means of which the valve is lifted off its seat. The parts at the left hand end of the figure are shown in plan for the sake of clearness.

Fig. 2 is a vertical section through the pump on the line 2—2 of Fig. 1 looking in the direction of the arrows.

Fig. 3 is a somewhat diagrammatic perspective view showing the disposition of the regulating mechanism and the relationship between the pump control device and the float which actuates it.

Like letters indicate like parts throughout the drawings.

In the float construction the spindle A on which the float B is mounted passes through the wall of a casing C which incloses the float and is in communication with the steam generator D so that water can freely enter the casing from the generator. The float spindle A has imparted to it a constant reciprocating movement in the direction of its axis so as to maintain the bearings of the spindle free and permit the float B to move freely under the influence of the varying water level. This reciprocating movement may conveniently be derived from a suitably disposed rock shaft E provided with two lever arms E' and E'' and the shaft is rocked by suitable mechanism connected to the arm E'. The arm E'' is connected by a link E''' with one arm F of a two armed lever pivoted at F' on some fixed part. On the end of the other arm F'' of this lever is a member F''' which abuts against the ends of the float spindle A. As will be seen by means of this mechanism when the shaft E is rocked the lever F will be oscillated and the spindle A will be moved thereby either in both directions by means of a bridle gear or the lever may move the spindle in one direction only the return movement being effected conveniently by means of a spring not shown in the drawings. The general arrangement of this mechanism is illustrated in Fig. 3.

The feed pump employed may be of any known construction but conveniently as shown in Fig. 1 the delivery valve G is mounted in the pump casing H opposite to the suction or inlet valve J. There is ar-

ranged beneath the suction valve J a spindle J' which can slide in a guide member G' formed in the pump casing. The upper end J² of the spindle J' loosely engages the 5 underside of the valve J while the lower end J³ of the spindle projects beyond the end of the guide member G' into a chamber G² of suitable dimensions formed within the pump chamber below the valve G. The 10 end J³ of the valve spindle J' bears against or can be acted on by a lever K mounted on the end L of a rockshaft which extends through the wall of the pump chamber G² into which chamber the water enters on its 15 way to the suction valve J. When the shaft L is turned it will cause the lever K to so act on the spindle J' as to slide this spindle in the guide G' and lift the valve J off its seat sufficiently to insure that water 20 drawn in by one stroke of the pump will on the return stroke be delivered back again into the supply tank through the ports which would normally be covered by the suction valve J.

25 A stuffing box G³ of suitable construction is provided where the rockshaft L passes into the pump chamber G². The shaft L is conveniently formed in two lengths the second part L' being connected to the part 30 L by a flexible ring L² or in some other manner which will allow of slight flexure of the shaft in order to obviate the necessity for strict alinement of the bearings in which the shaft is mounted. One of these 35 bearings is constituted by the stuffing box G³ while the other bearing M is conveniently arranged at the opposite end of the shaft length L'. There may also be an intermediate bearing not shown in Fig. 1. 40 The joint L² between the two parts L and L' of the shaft may be formed in any convenient manner but preferably as shown there is a boss L³ at the end of the shaft part L and between this boss and the stuffing 45 box G³ is a coiled spring N which so acts on the shaft L L' as to tend to draw its end through the stuffing box G³ out of the pump chamber G².

The end L⁴ of the shaft part L' which is 50 opposite to the coupling L² and is carried in the bearing M, lies against one arm O of a bell crank lever pivoted at some fixed part at O'. The end of the shaft and a part of the lever with which it is in contact are 55 hardened or a steel ball is disposed between these parts or the construction is otherwise so as to provide where these parts are in contact bearing surfaces adapted to stand wear. The other arm O² of the bell crank 60 lever is connected by a link O³ with the lever arm E² on the rockshaft E. Thus when this shaft is turned in the manner described by power applied to the lever arm E' the bell crank lever O O² will be moved 65 and the shaft L L' will be forced in the di-

rection of its axis against the action of the coiled spring N which returns the shaft after the lever O has completed the movement in one direction. A constant reciprocating movement is thus imparted to the 70 shaft L L' which is in this way kept free in the stuffing box G³ so that the float as it moves can without undue resistance cause the shaft L L' to be turned about its axis. As is apparent the reciprocation of the 75 float spindle A is effected simultaneously with the reciprocation of the shaft L L'.

The movements of the float B are communicated to the shaft L L' by means of a lever A' on the float spindle A which is 80 connected by a link A² to a lever L⁵ mounted on the part L' of the shaft which controls the pump valve. The connections between these levers and the link are such as to allow for the reciprocating movements 85 which are imparted respectively to the float spindle A and to the shaft L'.

For the sake of clearness in Fig. 1 the left hand part of that figure as already indicated is in plan so as to show the positions of the 90 levers L⁵ and O O² and the correct relationship of these levers with the other parts of the mechanism is apparent from Fig. 3. In the latter figure the pump casing is omitted and the pump suction valve J is diagrammatically illustrated with its spindle J' in 95 relation to the lever K. The spring N and other parts are also omitted for the sake of clearness.

The details of construction may be varied 100 in accordance with requirements and the type of generator, float and pump with which the above described mechanism is employed.

What I claim as my invention and desire 105 to secure by Letters Patent is:—

1. In apparatus for regulating the feed water supply of steam generators the combination of a steam generator, a feed water pump, a rockshaft extending through the 110 wall of the pump casing adjacent to the suction valve of the pump, a lever mounted on the rockshaft within the pump casing and adapted to lift the suction valve off its seat when the shaft is rocked, mechanism to 115 which movement is imparted by variations in the level of the water in the steam generator, means by which the movements of this mechanism are communicated to and rock the shaft, mechanism by means of 120 which axial movement is imparted intermittently to the rockshaft in one direction, and a spring operative to move the rockshaft in the opposite direction as set forth.

2. In apparatus for regulating the feed 125 water supply of steam generators the combination of a steam generator, a feed water pump, a rockshaft extending through the wall of the pump casing adjacent to the suction valve of the pump, a lever mounted on 130

the rockshaft within the casing and adapted to lift the suction valve off its seat when the shaft is rocked, a float disposed so as to be subject to and movable by variations in the 5 level of the water in the generator, means by which the movements of the float are communicated to and rock the shaft, mechanism by means of which axial movement is imparted intermittently to the rockshaft in 10 one direction, and a spring operative to move the rockshaft in the opposite direction as set forth.

3. In apparatus for regulating the feed water supply of steam generators the combination of a steam generator, a feed water 15 pump, a rockshaft extending through the wall of the pump casing adjacent to the suction valve of the pump, means for reciprocating this shaft in the direction of its axis, a lever mounted on the rockshaft within the 20 pump casing and adapted to lift the suction valve off its seat when the shaft is rocked, a chamber in such communication with the steam generator that water from the generator can freely enter and partly fill the 25 chamber, a rotatable spindle which extends through the wall of the chamber, a float mounted on the spindle within the chamber so that it can rise and fall as a result of variations in the level of the water in the 30 chamber and thereby rotate the spindle, a rockshaft in the opposite direction, a chamber in such communication with the steam generator that water from the generator can freely enter and partly fill the chamber, a rotatable spindle which extends through the 35 wall of the chamber, a float mounted on the spindle within the chamber so that it can rise and fall as a result of variations in the

level of the water in the chamber and thereby rotate the spindle, and means by which the rotary movements of the float spindle 35 are communicated to the rockshaft as set forth.

4. In apparatus for regulating the feed water supply of steam generators the combination of a steam generator, a feed water 40 pump, a rockshaft extending through the wall of the pump casing adjacent to the suction valve of the pump, means for reciprocating this shaft in the direction of its axis, a lever mounted on the rockshaft within the 45 pump casing and adapted to lift the suction valve off its seat when the shaft is rocked, a chamber in such communication with the steam generator that water from the generator can freely enter and partly fill the 50 chamber, a rotatable spindle which extends through the wall of the chamber, a float mounted on the spindle within the chamber so that it can rise and fall as a result of variations in the level of the water in the 55 chamber and thereby rotate the spindle, means by which the rotary movements of the float spindle are communicated to the rockshaft, and means for reciprocating the float spindle in the direction of its axis as 60 set forth.

In testimony whereof I have signed my name to this specification.

THOMAS CLARKSON.
